CLAIM

Related U.S. Application Data

(63) Continuation of application No. 29/305,315, filed on Mar. 18, 2008.

The ornamental design for a lid assembly with a reclosable drink opening, substantially as shown and described.

(51) **LOC (9) Cl.** **07-01**

DESCRIPTION

(52) **U.S. Cl.** **D7/396.2; D9/447**

FIG. 1 is a top perspective view of the lid assembly of this invention partially obscured by the sliding member thereof which is shown in its open position in broken lines;

(58) **Field of Classification Search** D7/396.2,

FIG. 2 is a top perspective view of the lid assembly of this invention with the sliding member thereof which is shown in its closed position in broken lines;

D7/396.1, 387, 900, 396; D9/435, 455, 434, D9/449, 445, 438, 441, 439, 436, 443, 447; 206/807; 215/235, 237; 220/254.1, 254.3, 220/345.3, 254.6, 270; D20/28; 222/480

FIG. 3 is a top view of the lid assembly of FIG. 2, where broken lines representing an overhanging lip portion of the lid assembly near a drink opening illustrated in other views have been removed in order to show the full claim;

See application file for complete search history.

FIG. 4 is a top perspective view of the cover element of the lid assembly of this invention with sliding member omitted;

(56) **References Cited**

FIG. 5 is a bottom perspective view of the cover element of the lid assembly of FIG. 4; and,

FIG. 6 is a front view of the cover element of FIG. 4.

U.S. PATENT DOCUMENTS

The portions shown in broken lines are included to show environment in which the item is used and form no part of the claimed design.
